DESIGN FOR A SIGN

Scott S. Bair, Westminster, Md.

Application April 19, 1938, Serial No. 76,611

Term of patent 14 years

To all whom it may concern:

Be it known that I, Scott S. Bair, a citizen of the United States of America, residing at Westminster, county of Carroll, and State of Maryland, have invented a new, original, and ornamental Design for a Sign, of which the following is a specification, reference being had to the accompanying drawing forming a part thereof, wherein:

I claim:

The ornamental design for a sign, as shown.

SCOTT S. BAIR.
